UNITED STATES PATENT OFFICE.

WILLIAM L. BEAN, OF WEST HAVEN, CONNECTICUT.

LOCOMOTIVE-SMOKE-BOX STRUCTURE.

Original application filed June 2, 1925, Serial No. 34,405. Divided and this application filed April 2, 1926. Serial No. 99,416.

This invention relates to locomotive smoke-box spark nettings. The invention will be best understood by reference to the following description, when taken in connection with the accompanying drawings of one specific embodiment thereof, while its scope will be more particularly pointed out in the appended claims.

In the drawings:

Fig. 1 is a longitudinal, vertical, sectional view of a locomotive smoke-box structure having a spark netting exemplifying the invention;

Fig. 2 is a front elevation of the spark netting;

Fig. 3 is a sectional view on an enlarged scale on line 3—3 of Fig. 2;

Fig. 4 is a sectional view on an enlarged scale on line 4—4 of Fig. 2; and

Fig. 5 is a sectional view on an enlarged scale on line 5—5 of Fig. 2.

Referring to the drawings, and to the embodiment of the invention which is selected for exemplification, and having reference at first more particularly to Fig. 1, the smoke-box structure comprises a smoke-box, which in the present example is a casting having a circumferential wall 22, and a stack 23. The smoke-box has an opening 24 for an exhaust pipe 25, the exhaust from which is directed upward into and through the stack, and thereby induces a draft in a well known manner.

The deflector which deflects the gases in a downward direction, and compels them to flow first to the forward end of the smoke-box and thence in an upward and rearward direction through the spark netting into the path of the exhaust steam toward the stack, will now be described, reference being had at first to Fig. 1. The deflector comprises a rear, generally upright portion, designated generally by the numeral 26, and a lower, generally horizontal portion designated by the numeral 27.

The spark netting will now be described, reference being had at first to Fig. 2. The netting in the present example comprises left and right sections 28 and 28', and a door section 29. The sections 28 and 28' lie in one plane, and together have a circular margin, which is received in a groove 30 (see Fig. 5), presented by a projection 31, herein formed as an integral part of the circumferential wall 22 of the smoke box casting.

This construction, therefore, provides a tongue and groove joint, having the advantage that it prevents the escape of sparks through the joint, and yet does not call for the use of bolts to draw the joint together to make it tight. Moreover, the sections of the spark netting can be inserted into and withdrawn from the groove very conveniently. The lower margins of the sections 28 and 28', as well as the lower margin of the door section 29, are received in a groove 32 (see Fig. 1) provided in a projection 33, herein formed as an integral part of the lower horizontal portion 27 of the deflector.

Referring now to Fig. 3, the spark netting sections 28 and 28' are joined together by a bar 34, which presents oppositely disposed grooves 35 and 35', in which adjacent edges of the sections 28 and 28' are received. This provides a joint which prevents the passage of sparks, and which nevertheless permits the parts to be assembled and dismounted with ease, as the bar can be removed by simply sliding it lengthwise out of its place, when the door section 29 is absent. On the other hand, when the door section is in place, it locks the bar in place. In the present example, the bar is further secured by the use of cotter pins 36, which extend through opposite walls of the bar, and thence through interstices of the netting section 28.

The door section is mounted in a somewhat similar manner (see Fig. 4), it being received in a frame composed of bars such as the bar 37, having a groove 38, which receives the adjacent edge of the netting section 28. The bars may be secured to the netting sections by welding them together, as indicated at 39. Each bar which forms a part of the door frame presents a recess 40 for the marginal portion of the door, which may be secured in place by appropriate fastening means, such as pins 41 and keys 42.

The spark netting structure as thus far described has its marginal portion throughout received in grooves which securely hold it in place, but to prevent any possibility of the front edge of the lower horizontal portion 27 of the deflector sagging or warping, due to its exposure to the hot gases, the spark netting may be used as a means of support for such portion of the deflector. To this end, in the present example the upper corners of the spark netting sections 28 and 28' are secured in the groove 30 of the pro-

jection 31, by pins, such as the pin 43 (see Fig. 5), held in place by the cotter pin 44, while the lower corners are held in place in the groove 32 (see Fig. 1) of a projection 33 by similar pins 45.

Thus it is evident that there is no possibility of warping of the parts, which might permit sparks to pass through the joints, while at the same time, the simplicity of the arrangement is such that the door section of the spark netting can be removed and replaced with great facility, and if desirable, the remaining sections can be removed and replaced with equal ease.

15 This application is a division of my pending application for locomotive smoke-box structures, Ser. No. 34,405, filed June 2, 1925.

Having thus described one embodiment of the invention, but without limiting myself thereto, what I claim and desire by Letters Patent to secure is:

1. In a smoke-box structure, the combination of a smoke-box and a spark-netting therein and having a margin supported by 25 said smoke-box, said spark netting comprising two netting sections, and a bar provided with a groove which receives an edge of one section and a recess which receives an edge of the other section.

30 2. In a smoke-box structure, the combination of a smoke-box and a spark-netting therein and having a margin supported by said smoke-box, said spark netting comprising two netting sections, and a bar provided 35 with two grooves which receive adjacent edges, respectively, of said sections.

3. In a smoke-box structure, the combination of a smoke-box and a spark-netting therein, and having a margin supported by 40 said smoke-box, said spark netting comprising two netting sections, and a bar provided with two oppositely facing grooves which receive adjacent edges, respectively, of said sections, said bar being mounted to slide 45 lengthwise into and out of position between said sections.

4. In a smoke-box structure, the combination of a smoke-box and a spark-netting therein and having a margin supported by 50 said smoke-box, said spark netting comprising three netting sections lying in a common plane, two sections together defining a doorway and the third section constituting a door, a bar provided with two grooves which receive adjacent edges, respectively, of said 55 two sections, and bars which constitute a door frame on three sides of said doorway and which bars have recesses which receive marginal portions of said door section and grooves which receive marginal portions of said two sections.

5. In a smoke-box structure, the combination of a smoke-box having a pair of flanges separated by a groove, a spark-netting comprising two sections having edges received in

70 said groove and having other edges spaced apart, and a bar having a portion disposed between such other edges, said bar having a pair of flanges which embrace one of such other edges, and a pair of flanges which embrace the other of such edges.

6. In a smoke-box structure, the combination of a smoke-box having a pair of flanges separated by a groove, a spark-netting comprising two sections having edges received in 75 said groove and having other edges spaced apart, a bar having a portion disposed between such other edges, said bar having a pair of flanges which embrace one of such other edges and a pair of flanges which embrace the other of such edges, and fastening 80 elements extending through the first-mentioned pair of flanges and through said sections, respectively.

7. In a smoke-box structure, the combination of a smoke-box having a pair of flanges separated by a groove, a deflector having a pair of flanges separated by a groove, a spark-netting comprising a plurality of sections having edges received in 85 said grooves, and having other edges spaced apart, fastening elements extending through said flanges and through the interposed sections, bars having portions disposed between such other edges, one of said bars having oppositely disposed grooves which receive two 90 of such other edges, and other bars having grooves which receive still other edges.

8. In a smoke-box structure, the combination of a smoke-box and a spark-netting 100 therein, comprising two sections extending in the same general direction and disposed edge to edge, and a bar having a portion disposed between said edges, said bar being provided with a groove which receives one 105 of said edges, and a recess which receives the other of said edges.

9. In a smoke-box structure, the combination of a smoke-box and a spark-netting 110 therein, comprising two sections lying in a common plane and having adjacent edges spaced apart, and a bar having a portion disposed between said edges, said bar having two flanges which embrace one of said edges, and a flange which overlies the other of 115 said edges.

10. In a smoke-box structure, the combination of a smoke-box and a spark-netting therein, comprising two sections having adjacent edges spaced apart, and a bar having a portion disposed between said edges, said bar having a pair of flanges which embrace one of said edges, a single flange which overlies the other of said edges, and a fastening element which extends through said flange 125 and through the section the edge of which such flange overlies.

11. In a smoke-box structure, the combination of a smoke-box and a spark-netting therein, comprising two sections having ad- 130

5 jacent edges spaced apart, and a bar having a portion disposed between said edges, said bar having a pair of flanges which embrace one of said edges and a pair of flanges which embrace the other of said edges.

12. In a smoke-box structure, the combination of a smoke-box and a spark-netting therein, comprising two sections having adjacent edges spaced apart, and a bar having 10 a portion disposed between said edges, said

bar having a pair of flanges which embrace one of said edges, a pair of flanges which embrace the other of said edges, and a fastening element which extends through the flanges of one pair and through the section 15 the edge of which such flanges embrace.

In testimony whereof, I have signed my name to this specification.

WILLIAM L. BEAN.
